HENRY READ, OF TULSA, OKLAHOMA

CONCRETE FLOOR JOIST FORM CONSTRUCTION

Application filed July 29, 1929. Serial No. 381,719.

This invention relates to concrete joist formwork construction, and more especially to a construction of the character named for cooperative relationship with floor slab formwork.

In a prior invention I provided a floor slab formwork construction which could be readily sprung or bowed downward to withdraw it from its support so that it could be used for another floor before the concrete upon it was sufficiently cured to carry a load, the advantage of such type of floor slab formwork permitting a contractor to lay the floors of a building with fewer floor slab forms than is necessary where the formwork must remain in position for each floor until the concrete is fully cured.

My particular object in this invention is to make a similar provision for the joist formwork so that the latter can be removed at the same time that the floor slab formwork is removed and used for another floor before the concrete of the floor from which they are withdrawn is fully cured. Another object is to provide a construction which simplifies and cheapens the work of laying concrete floors and at the same time facilitates the progress of such work.

With the above and other objects in view as hereinafter appear, the invention consists in certain novel and useful features of construction and combinations of parts as hereinafter described and claimed; and in order that it may be fully understood, reference is to be had to the accompanying drawing, in which:

Figure 1 is a fragmentary perspective view showing a joist formwork for concrete joist construction, embodying the invention, the drawing also disclosing floor slab forms preferably used in conjunction with the joist formwork, and other complementary features.

Figure 2 is a section taken on the line II-II of Figure 1.

Figure 3 is a section taken on the line III-III of Figure 1.

Figure 4 is an enlarged fragmentary perspective view showing one of the brackets which carry the sides of the joist form as a unit, one of the spreaders or cross bars for

bracing the adjacent joist forms in fixed relation and for supporting the flooring forms between the joist forms, and one of the locks for holding the spreaders in interlocked relationship with the bracket.

Referring to the drawing in detail, 1 indicates a pair of channel iron or equivalent beams of a building, and 2 stringers secured in any suitable manner to said beams. The beams may be any suitable distance apart. If spaced a substantial distance apart, for example 16 feet apart, it is desirable to provide an intermediate support centrally between the beams. As shown in Figure 1 said support is in the form of a horizontal 4×4 or equivalent member 3 extending parallel with the beams, and is arranged with its upper face in the plane of the upper edges of the stringers 2. Each 4×4 will rest upon a suitable number of vertical shorers 5, one only being shown. The shorers as customary are provided with scabs 6, and overlying the latter and fitting against opposite sides of each shorer is a pair of stringers 7 which parallel the member 3 and are flush with the upper face of the same. Wedges 8 or any other suitable means are interposed between the scabs and the stringers to insure that the upper edges of the latter are at the proper height which, as stated, is in the plane of the upper side or face of the member 3.

In a construction where the intermediate support construction described is employed, it will be preferable to aline joist forms, the same resting at their adjacent ends on the stringers 7 and at their opposite other ends on the respective stringers 2 of the beams 1. This arrangement leaves a gap between the adjacent ends of the sides 9 of the joist forms, and means are provided to close said gaps, as hereinafter described.

The sides of each joist form, which preferably converge downward slightly, are fastened together as a unit by oppositely-facing angle brackets 10, the upper arms of the angle brackets being secured respectively to the outer faces of the sides of the joist forms, and the other arms extending horizontally below said joist forms' sides and standing in overlapped relationship, suitable means such

- as bolts and nails being employed to adjustably secure the overlapping portions of the brackets together, the adjustment being necessary so that the sides can be disposed at 5 distances apart to correspond with the width of the concrete joist to be provided between them. There will be a bracket construction such as described near each end of each pair of sides, and any desired number of extra 10 or intermediate brackets of the same type necessary to insure rigidity of the joist forms and proper support of floor slab forms, hereinafter identified, Figure 1 showing two of such intermediate bracket constructions. 15 The upstanding arms of the brackets are of channel form, with the channel faces juxtaposed to the respective sides 9, and at their upper ends the upright portions are notched to provide upwardly-facing shoulders 11. 20 To constitute braces between the adjacent joist forms, cross bars or spreaders 12 are employed, each spreader resting on the shoulders 11, of opposite brackets, and having arms or tongues 13, projecting between the 25 upper ends of the brackets and the joist sides 9 to which such brackets are secured. The spreaders 11 thus serve to not only brace adjacent joist forms against approaching movement but also serve to prevent them from 30 spreading apart. The spreaders are preferably of channel construction.
- To guard against accidental disengagement of a spreader from its engaged brackets, a pair of similar channel locking devices 14, 35 are employed. These devices are provided with short longitudinal slots 15, terminating at their outer ends in offsetting slots 16, the latter converging downward slightly with respect to the ends of the locking devices abutting 40 the spreaders to hold them in the notches of the brackets. The slots of the locking devices pivotally and slidably engage nails, screws or the like 17 driven into the adjacent sides of the joist forms. When a locking 45 device is to be disengaged from a spreader, it is tapped upward lightly at its pivoted end so that, because of the inclination of the offsetting portion of the slot, it shall move endwise to withdraw slightly from the engaged 50 spreader. If this does not result in the locking device swinging downward to inoperative position, force can be applied to slide it slightly with the pivot engaging the portion 55 of the slot. When it is moved enough, the locking device will be free to swing down to a pendant or inoperative position. The reverse manipulation of the locking device is followed in disposing it in operative position with relation to the spreader. 60 The joist forms are provided with soffits 18, which rest upon the brackets uniting the sides of such forms. Where the beams are spaced apart sufficiently to require the intermediate supporting member 3 and stringers 7, so that 65 a gap or space is left between aligned joist

forms, the ends of the soffits 18 adjacent the intermediate support, should be about flush with the outer faces of the stringers 7, so that the latter are not in the way when the soffits are to be withdrawn, as hereinafter referred to. The space thus left between adjacent ends of aligned soffits 18, is filled by short soffits 19 which rest squarely upon the member 3 and the stringers 7, and cannot be removed after the concrete material is applied, until the shorers and the said stringers 7 and member 3 are taken down, which is not until the concrete is thoroughly set and the whole floor work is self-supporting.

Any suitable floor form or floor forms may be employed. In the construction shown two floor forms are arranged in longitudinal alignment between the beams 1. They each consist of a sheet metal top plate 20 secured to underlying spaced strips 21 extending parallel with the joist forms and therefore transversely with respect to the beams. The two floor forms preferably terminate at their ends over the stringers 2 and 7 thus leaving an uncovered joint between them like that between the adjacent ends of aligned joist forms. These spaces must be covered, and to accomplish this metal saddles 22 of inverted U-form are fitted down upon the adjacent ends of aligned floor forms and joist forms, as shown clearly in Figures 1 and 2, the arms 23 thus closing the spaces between the engaged joist form sides and, by engagement with the latter, are prevented from endwise slippage. The spaces at the opposite ends of and below the floor forms, viz., where the latter are contiguous to the beams 1, may be closed in any suitable manner, as by filling strips 24 upon the underlying stringers 2, one filler strip being shown in Figure 1.

With the parts arranged as explained it will be apparent that the concrete material in plastic form, can be deposited or poured so as to fill the beams if of the U-type shown, and also fill the joist forms and spread over the floor forms and the saddles to the required depth.

When the concrete has set for a sufficient length of time, to be self-supporting for short spans when bearing no load, the locking devices can be loosened and the spreaders removed. This permits the floor forms to be bowed down and lowered from position, the forms bowing downward sufficiently, as indicated by the dotted line in Figure 2, to permit them to clear the upper edges of the underlying arms of the brackets of adjacent joist forms. If it is desired then to remove the joist forms, the wedges are loosened and the stringers 7,—usually nailed in a few places for safety,—are pried off. The joist sides and the main soffits 18, and the saddles can then be taken down, leaving the short soffits 19 on the beam 3 in place until the concrete is fully cured and the shores are removed. The

removal of the joist forms, as units, is made easy by tapering the end extremities upward slightly, as, if the ends were vertical, some care would have to be exercised to hold them 5 against tilting in order to pass them downward readily between the member 3 and the beams 1. It is also desirable that the sides of the joist forms shall converge downwardly, as shown, to facilitate their withdrawal, with 10 the main soffits, from the partly cured concrete joists without chipping the latter.

From the foregoing it will be apparent that where the span between beams is twice or a greater multiple of the length of the floor 15 forms and joist forms, which are preferably about 8 feet long, it is necessary to use an intermediate support or supports, and the support or supports, represented here by the shorers, member 3 and the short soffits, re- 20 main in place until the concrete is completely cured. It has been found however that there is no necessity for leaving the stringers and floor and joist forms and saddles in place for more than one-fourth of the full curing 25 period. Because of this fact it is possible, when pouring not more than one floor a week, to employ only one set of the parts last named for the entire building, whereas the equipment of shorers, member 3 and the short 30 soffits must be in full for each floor of the building, until the concrete is fully cured, a period of from fourteen to twenty-one days.

It will be apparent from the drawing and description that I have produced a construction 35 which is susceptible of modification in various details within the principle of construction and mode of operation involved, and therefore within the spirit and scope of the appended claims.

40 I claim:

1. Spaced supports, a joist formwork resting at its ends on said supports and consisting of parallel sides, angle brackets secured to and underlying the sides and secured to 45 together in pairs, the arms of the brackets engaging the sides, having portions spaced from the latter and also having upwardly-facing shoulders, a horizontal spreader resting at one end on each shoulder and provided with a laterally-projecting tongue fitting in the said 50 space between the respective formwork side and bracket, a locking device fitting against the joist side and endwise against the side of the corresponding spreader to hold the latter 55 on the shoulder of the bracket and the tongue in the said space, and provided with a longitudinal slot terminating at its end remote from the spreader in an extension disposed in 60 downwardly-converging relation to the en- gaged side of the spreader, and a pin piv- otally and slidably engaged by the slot and secured to the adjacent joist formwork.

2. In a concrete floor joist form construc- 65 tion, spaced supports, hollow joist forms rest- ing at their ends on adjacent supports, op-

posite-upright arms secured to the near sides of adjacent joist forms and terminating short of the upper edges of said sides, a horizontal spreader between and disposed below the plane of the upper edges of said forms and resting upon the said arms and also engaged with said arms to prevent relative spreading movement thereof, and means pivotally and longitudinally movably mounted on said forms for engagement with and disengage- 70 ment from the spreader to hold the latter against accidental disengagement by side- wise movement, from the said arms.

3. In a concrete floor joist form construc- 75 tion, spaced supports, hollow joist forms rest- ing at their ends on adjacent supports, oppo- site-upright arms secured to the near sides of adjacent joist forms and terminating short of the upper edges of said sides, a horizontal spreader between and disposed below the plane of the upper edges of said forms and resting upon the said arms and also engaged 80 with said arms to prevent relative spreading movement thereof, means pivotally and lon- gitudinally movably mounted on said sides 85 for engagement with and disengagement from the spreader to hold the latter against accidental disengagement by sidewise move- 90 ment, from the said arms, and a floor slab form fitting snugly between adjacent joist 95 forms and resting directly upon said spreader.

In testimony whereof I affix my signature.
